DESIGN FOR A SWEATER

Eugene I. Itsckowitz and Leo Greenstein, Brooklyn,
N. Y.

Application April 1, 1938, Serial No. 76,216

Term of patent 3½ years

To all whom it may concern:

Be it known that we, Eugene I. Itsckowitz and Leo Greenstein, citizens of the United States and residents of the Borough of Brooklyn, in the city and State of New York, have invented a new, original, and ornamental Design for a Sweater, of which the following is a specification, reference being had to the accompanying drawing, forming a part thereof.

The figure shown in the drawing is a rear plan view of a sweater showing our new design, the remainder of the body and sleeves of the garment

being in dotted outline. The design on the front of the sweater is like that on the rear.

The dominant feature of our new design is the ornamentation on the lower part of the sweater body, which ornamentation is also repeated on the cuffs.

We claim:

The ornamental design for a sweater substantially as shown and described.

EUGENE I. ITSKOWITZ.
LEO GREENSTEIN.
